UNITED STATES PATENT OFFICE.

ALEXANDER S. SPEER, OF CHICAGO, ILLINOIS, ASSIGNOR TO THE ROOFING PATENTS COMPANY, A CORPORATION OF DELAWARE.

SHINGLE STRIP.

1,412,295.

REISSUE

Specification of Letters Patent. Patented Apr. 11, 1922.

Application filed November 12, 1918. Serial No. 337,577.

To all whom it may concern:

Be it known that I, ALEXANDER S. SPEER, a citizen of the United States of America, and resident of Chicago, county of Cook, 5 and State of Illinois, have invented certain new and useful Improvements in Shingle Strips, of which the following is a specification, and which are illustrated in the accompanying drawings, forming a part 10 thereof.

The invention relates to prepared roofing and particularly to that which is formed in strips having notches extending transversely into the strip at intervals along one edge of 15 the same to simulate the appearance of separate shingles when the strips are laid upon the roof in overlapping relation. The object of the invention is to provide a new form of shingle strip which affords more 20 complete protection for the roof upon which it is laid and involves an economical use of the sheet material from which the shingle strips are produced.

In the accompanying drawings:—

25 Fig. 1 is a plan view showing a plurality of the improved shingle strips laid upon the roof, the relative position of the upper or covered edge of one of the shingle strips with respect to the superimposed strips being indicated by dotted lines;

Fig. 2 is a plan view of the web and a severed shingle strip, Figs. 3 and 4 are plan views of alternate forms of shingle strips.

The improved shingle strip 10 is preferably of sufficient length to comprise a plurality of connected shingle tabs 11, shown as four in number, with intervening slots or gutters 12. These shingle tabs constitute the portion of the strip which is exposed to 35 the weather, when in use, and a desirable ornamental appearance and other advantages are obtained without in anywise detracting from the utility of the strip, if each of the shingle tabs 11 is formed with chamfered 40 corners 13. Preferably the line of chamfering of the corners 13 extends at any angle of 45° to the front edge of the strip and reaches to half the length of the intervening slots or gutters 12. The slots or 45

50 gutters have parallel side walls, so that each shingle tab has over a portion of its length parallel side edges. The slots or gutters are of a depth corresponding to the amount of weather given the shingle strips. Thus

when laid each shingle tab will be separated 55 from adjacent tabs by the slots or gutters, the said slots or gutters extending the full width of the strip exposed to the weather, as clearly shown in Figure 1.

Under these circumstances the remainder 60 of the strip 10 may comprise, without waste of material, a continuous body portion 14 having the full width usually provided for the portion of a shingle strip which is to be covered by succeeding layers of similar 65 strips, when in use, and a series of extensions 15 arranged along the back or covered edge 16 of the strip in line with the gutters or slots 12. It follows that if each of the 70 extensions 15 conforms in shape with the material removed from between the outer 75 end portions of two adjacent shingle tabs 11, a plurality of the shingle strips 10 may be completely formed from a length of web 17 equal only to the combined widths of the 80 strips from the free edges of the shingle tabs 11 to the rear edge 16 of the main body portion 14 of the strip. When this construction is used the only part of the original web 17 which is discarded comprises 85 the short tongues 18 (Fig. 2) removed from the inner end portions of the slots 12 while the full width of the shingle strips 10 from the free edges of the shingle tabs 11 to the rear edge 16 of the main body portion 14 of 90 the strip may be only two and one-half times the length of the shingle tabs and still permit of the strips being laid upon the roof with the full length of the shingle tabs exposed to the weather and with two full layers of roofing material covering all parts of the roof to the inner ends of the gutters or 95 slots 12. The strips are desirably fastened to the roof as usual with nails 19 introduced just above the inner ends of the slots 12. 100 The nails are thus covered by the shingle tabs 11 of the next overlying strip and each one of the extensions 15 is firmly held to the roof by reason of its position under two overlying strips which are in turn fastened to the roof at a point immediately beyond the end of the extension.

The strips 11 and discarded tongues 18 are conveniently cut from the web 17 by means of the machine forming the subject of Patent No. 1,249,544 granted to me December 11, 1917.

It will be understood that the shingle tabs

11 may have rounded ends, as 30 (Fig. 3) or curved corners as 31 (Fig. 4), the respective extensions 33 and 34 corresponding, generally, to the spaces between adjacent shingle tabs.

5 I claim as my invention:—

10 1. A shingle strip having spaced transversely extending slots in one side edge, dividing the strip at the said edge into shingle tabs, the slots extending the full depth of the strip to be exposed to the weather when laid, whereby to cause the strips when laid with the slotted edge of each succeeding strip at the inner ends of the slots of the 15 preceding strip to present the appearance of individual shingles, each strip having an aggregate width of twice the length of a shingle tab, and having projecting tabs in alinement with the slots whereby when the 20 strips are laid as above specified, there will be two layers of strip beneath each slot.

25 2. A shingle strip having one edge slotted at intervals over the depth of the strip to be exposed to the weather to form shingle tabs, and having at the opposite edge, and in alinement with the slots, projecting tabs, whereby to reinforce and strengthen the strip transversely at the slots, the strip having a minimum width greater than the 30 length of a shingle tab, whereby when the strips are laid with the slotted edge of each strip flush with the inner end of the slots of the preceding strip the laid roof will present the appearance of individual shingles, and beneath each slot there will be two 35 layers of strip.

40 3. A shingle strip having at one side edge a plurality of shingle tabs separated and spaced apart from each other on lines extending transversely of the strip and of a depth corresponding to the width of the lap to be exposed to the weather, the inner ends of the lines of separation between the shingle tabs being slots having parallel side 45 walls, the shingle tabs being of a length less than half the width of the strip and the strip having laterally extending tabs at the opposite side edge from the shingle tabs and in alinement with the slots, where- 50 by when the strips are laid inlapping re-

lation, there will be two layers of strip beneath each slit.

4. A shingle strip comprising a weather portion composed of a plurality of equal shingle tabs separated on lines extending transversely of the strip and of a depth corresponding to the width of the lap to be exposed to the weather, the inner ends of the lines of separation being slots with parallel side walls, a body portion to 60 which the tabs are connected of a width greater than the length of a shingle tab and less than a multiple of the length of the said tab, and projections at the far edge of the body portion from the shingle tabs 65 spaced in accordance with the spacing of the said slots and alining with the slots, each of the said projections being of a length equal to the difference between the width of the body portion and the said multiple of the length of the shingle tabs. 70

5. A shingle strip having at one side edge similar shingle tabs spaced apart at their adjacent side edges by notches extending transversely of the strip and of a depth 75 corresponding to the width of the strip to be exposed to the weather, the inner ends of the notches having parallel side walls, and having at the other side edge laterally extending tabs, the strip having an aggregate width greater than twice the length 80 of the shingle tabs, and the laterally extending tabs being in alinement with the notches, whereby when the strips are lapped with the shingle tabs to the weather, there 85 will be two layers of shingle strip beneath each notch.

6. A shingle strip having at one side edge a plurality of shingle tabs separated and spaced apart from each other on lines extending transversely of the strip and of a depth corresponding to the width of the lap to be exposed to the weather, the inner ends of the lines of separation between the shingle tabs being slots having parallel side 95 walls, and the strip having laterally extending tabs on the edge opposite the shingle tabs and in alinement with said slots for the purpose described.

ALEXANDER S. SPEER.
